CAN POURING SPOUT

Frank Pollifrone, Tiburon, Calif.

Application May 13, 1937, Serial No. 142,441

3 Claims. (Cl. 221—23)

This invention relates to a can pouring spout and has for an object to provide a can pouring spout which may be attached to one edge of a can containing a liquid such as may be used in a household or garage.

A further object of this invention is to provide an attachable and detachable can pouring spout which may be attached to cans such as one or five-gallon cans, or even smaller ones, particularly those that are of rectangular shape and are intended to be emptied through a hole to be punched in a corner of the top. While this spout is particularly intended for cans of rectangular shape, as shown, it may likewise be used with cans of other shapes, on which, however, the spout will have to be made of a shape corresponding to the shape of the can. If used with a circular can, the spout would have to have a radius corresponding to the radius of the can, but if used with a rectangular can the same spout may be used with a large or small can.

A further object of this invention is to provide a can pouring spout which may be attached to the top edge of the can and thus not have to embrace the can in order to be secured thereto, thereby making it feasible for this spout to be attached to cans of large capacity, as well as cans of small capacity.

A further object of this invention is to provide an attachable spout which may be detached from the can and readily re-attached to the same or another can without necessitating the use of tools.

With the foregoing and other objects in view as will hereinafter become apparent, this invention comprises the constructions, combinations and arrangement of parts, hereinafter set forth, disclosed and shown on the accompanying drawings. In these drawings,

Fig. 1 is a top plan view of one form of the pouring spout of this invention attached to a rectangular can.

Fig. 2 is a side view of Fig. 1.

Fig. 3 is a sectional view on line 3—3 of Fig. 2.

Fig. 4 is a vertical sectional view on line 4—4

of Fig. 1, Fig. 5 or Fig. 8.

Fig. 5 is a perspective view of a pouring spout having a different type of attaching means.

Fig. 6 is a sectional view of the attaching means of Fig. 5.

Fig. 7 is a back perspective view of a spout having another form of attaching means.

Fig. 8 is a front perspective view of Fig. 7.

Fig. 9 is an elevational view of the operating cam of Figs. 7 and 8.

There is shown at 10 a representation of a

rectangular can such as used in quart, half-gallon, gallon or five-gallon sizes, either for household supplies such as fruit drinks, salad or olive oils, or the like, or for lubricating oils in the garage.

This can 10 has the usual side walls 11 to which is secured the top 12 with its usual overlapping flange or bead 13. Such cans 10 are usually intended to be opened by punching outlet hole 14 in the corner thereof, some cans having 10 the outline for such hole marked thereon.

The spout 16 of this invention is shaped to fit snugly about the corner of the can 10, being provided with a recessed channel 17, and depending wall 18, the recessed channel 17 fitting over the flange or bead 13 of the can top 12, while the depending walls 18 fit along the side walls of the can. Set in the recessed channel 17 is a sealing substance, such as at 19, adapted to be pressed against the bead 13 and making a tight fit therewith when the spout is secured to the sides of the can. Flaring upwardly and outwardly from the depressed channel 17 of the spout are the lips 20 leading to the end tip 21 to which the liquid from the can 10 will be directed 25 by the lips 20.

This invention contemplates different means of securing this spout to the edge of the can without the necessity of embracing the can. One such means is shown in Figs. 1 to 4, and includes 30 a spring clamp member 22 formed at each end of the spout 16. This spring clamp member 22 is formed by bending forwardly from the material of the spout 16 a pair of flanges 23 through which is secured a pivot pin 24. On the pivot 35 pin 24 is mounted a coil spring 25. The pin is journaled through a pair of tongues 26 extending from the clamp member 27. The spring 25 urges the clamp 27 to bring its lower edge 28 against the inner side of the spout wall 18. To 40 attach the spout 16 to the can 10 the clamp 27 is pressed backwardly against the spring 25 so as to bring its edge 28 over the up-turned edge of the can top 12 securing it in position. To 45 detach it the clamps are merely released in an obvious manner.

In Figs. 5 and 6 a different means of attaching the spout 16 is shown. In this form a long tongue 30 is left at each end of the spout and is bent downwardly as at 31. Aligned perforations 50 are punched in the upwardly and downwardly extending portions of the tongue 30 and bolt 32 and wing nut 33 pressed therethrough. To secure the spout 16 to the can 10 with this form of securing means it is only necessary to place 55

the spout with the edge of the tongue 30 extending over the flange or bead on the can top and tighten the wing nut 33. To remove the same the nut need only be loosened.

5. In Figs. 7, 8 and 9, still another securing means is provided and includes a downwardly turned flange 39 attached to fit over the can top flange or bead 13. A wire 40 is held in position on the spout by extending through a pair of out-struck tongues 41 in the wall 18 thereof. This wire 40 has hooked ends 42 overlying the downwardly turned flanges 39. A cam handle 43 is pivoted on the wire 40 and when turned down to the vertical position shown in Fig. 9 pulls the wire 40 away from the can and thus causes the hooks 42 to press the flange 39 against the inner sides of the bead 13 and hold the spout firmly in position.
- Having thus set forth and disclosed the nature 20 of this invention, what is claimed is:
1. A can pouring spout including a pair of pouring lips leading to a pouring tip there-between, side walls extending integrally from said pouring lips and means at the ends of said walls for cooperating with the can top edge to secure said spout to the can top edge, said means including an upwardly extending flange at each end of the pouring spout, the upper edge of said flange being turned downwardly to overlie the can top edge, and means to tighten the downwardly extending edge of the clamp against the can top edge, said tightening means including a bolt and nut extending through the upwardly and downwardly extending portions of said flange.
2. A can pouring spout including a pair of pouring lips leading to a pouring tip there-between, side walls extending integrally from said pouring lips and means at the ends of said walls for cooperating with the can top edge to secure said spout to the can top edge, said means including an upwardly extending flange at each end of the pouring spout, the upper edge of said flange being turned downwardly to overlie the can top edge, and means to tighten the downwardly extending edge of the clamp against the can top edge, said tightening means including a bolt and nut extending through the upwardly and downwardly extending portions of said flange.
3. A can pouring spout including a pair of pouring lips leading to a pouring tip there-between, side walls extending integrally from said pouring lips and means at the ends of said walls for cooperating with the can top edge to secure said spout to the can top edge, said means including an upwardly extending flange at each end of the pouring spout, the upper edge of said flange being turned downwardly to overlie the can top edge, and means to tighten the downwardly extending edge of the clamp against the can top edge, said tightening means comprising a hooked wire overlying said downwardly extending portion of said clamp and a cam member for forcing said hooked wire against said flange to tightening position.

FRANK POLLIFRONE.
